(57) **CLAIM**

The ornamental design for an electronic device, as shown and described.

DESCRIPTION

FIG. 1 is a front, top perspective view of an electronic device showing our new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate environmental structure and form no part of the claimed design. The gray shading represents a gray color. The darker gray shading on the rear panel and base ring represents the color black.

The thin black lines represent contour, not surface ornamentation. The diagonal dot-dash lines represent that the sides, top and bottom have a reflective finish.
